STOP RELAY MECHANISM FOR RECORD CONTROLLED MUSICAL INSTRUMENTS

Filed Jan. 29, 1924

Patented Sept. 7, 1926.

UNITED STATES PATENT OFFICE.

TOLBERT F. CHEEK, OF NEW YORK, N. Y., ASSIGNOR TO WELTE-MIGNON CORPORATION, OF NEW YORK, N. Y., A CORPORATION OF NEW YORK.

STOP-RELAY MECHANISM FOR RECORD-CONTROLLED MUSICAL INSTRUMENTS.

Application filed January 29, 1924. Serial No. 689,340.

This invention relates to record controlled musical instruments and particularly to those record controlled instruments where in the rewinding takes place, under control 5 of the record, at the conclusion of the musical selection.

In the manufacture of the present record controlled musical instruments such as pianos, great efforts have been made to utilize 10 all the space of the case in order that the parts of the player and expression mechanism may all be within the confines of the case without increasing the size thereof. At the same time, it has been the aim to have 15 the parts arranged in as few units as possible in order to permit of easy assembling and repair to the parts.

The primary object of this invention is the provision of improvements in the details of 20 the operating mechanism, and control valve for the sheet controlled rewinding mechanism.

Another object of my invention is the provision of a control valve and operating 25 mechanism therefor, for the stop-reply mechanism wherein the control parts are arranged at the rear of the tracker box and adjacent thereto.

Another object of my invention is the provision of a sheet controlled operating rock 30 shaft having its axis in line with the gravity operated valve.

Referring to the drawing wherein I have 35 illustrated a preferred embodiment of my invention,

Fig. 1 is a general view of the tracker box, roll operating mechanism and my improved control valve and its operating lever, the rear of the tracker box being shown 40 as being removed for clearness.

Fig. 2 is an enlarged view looking down 45 from above on my valve and its improved operating mechanism.

Fig. 3 is a fragmental cross sectional view 50 on the line 3—3 of Fig. 1.

Fig. 4 is a cross sectional view of the valve 55 box 57 which illustrates in detail also the construction of valve boxes 31 and 59.

9 designates the tracker box base board 50 of a record controlled musical instrument as a piano, 10 the tracker box mounted thereon, 11 and 12 the music and take up rolls respectively. 13 is the music sheet which operates over the tracker 14 in a well known 60 manner. At the right of the tracker box

is illustrated the winding and rewinding mechanism but as the details of this mechanism form no part of this invention, they will not be further described.

At 16, I have illustrated the shifting rod 60 which controls the position of the gears of the winding and rewinding mechanism. When the rod 16 is at the right in the position opposite to that shown in Figure 1, the gearing is in position to wind the sheet 65 onto the take-up roll 12 and to play as the note perforations register with the ducts of the tracker 14. The rod 16 is controlled by a hand lever (not shown) or by the replay pneumatic 17, the movable member of which 70 is provided with an extension 18 which engages a lug 19 on the rod 16, to move the latter to the right.

To operate the rod 16 to the left, a rewind pneumatic 20 is provided, which has an extension 21 on its movable member. This extension 21, engages the lug 22 on the rod 16 to move the rod to the left. A stop pneumatic 23 is provided with a connection from 75 its movable member, through a rod 24 to the electric switch 25. The switch 25, through the wires 26, controls the operation of the motor 27 which operates the main source of air tension 28.

The rewind pneumatic 20 is controlled 85 through the duct 31 and the usual primary pneumatic 31 by the duct 32 in the tracker. When the selection has been completely played, a perforation in the sheet causes 90 this duct to open with a result that the rewind pneumatic is caused to collapse and shift the rod 16 with a consequent rewinding of the record upon the music roll.

A depression 40 is provided in the take-up roll 12. Mounted, preferably along the 95 rear of the rear board 41 of the tracker box, are bearings 42 which carry a shaft 43. An arm 44 extending from the shaft 43, projects through the back board of the tracker box in position to have its end engage 100 the notch 40 in the take-up roll 12. When the music sheet is rolled upon the take-up roll, the arm 44 is prevented from entering the notch 40 as indicated by the full lines in Fig. 3.

At the end of the shaft 43 is a crank 45 which is in position to raise the stop-replay control valve 46. This valve 46 is pivoted at 46^a to a block supported at the rear of 110 the rear of the tracker box. The valve 46 is

normally held in lowered position by a weight 47. An extension portion 48 projects from the main body of the valve 46, and in position to be engaged by the crank 45 to cause the valve 46 to be lifted when the arm 44 enters the notch 40, the spring 49 always tending to force the shaft 43 to turn to force the end of the arm 44 into the notch 40 of the take-up roll 12.

10 A headed screw 50 limits the upward movement of the valve 46 and also prevents any tendency toward side movement which the valve might have.

15 A valve face 51 is provided for the valve 46 and is in position to engage a valve seat 52 which connects to a duct 53. A suitable material for the valve face has been found to be flexible leather.

20 The duct 53 is connected with a two-way valve 54 which connects with either the duct 55 or the duct 56, depending upon which way the switch is thrown.

25 The duct 55 connects with a valve box 57 containing the usual primary pneumatic which controls the exhausting or admission of air to the duct 58 which is in direct communication with the interior of the pneumatic 17.

30 The duct 56 connects with a valve box 59 containing the usual form of primary pneumatic which controls the exhaust from or admission of air at atmospheric pressure to, the stop pneumatic 23. The two-way valve 54 may be of any suitable design wherein 35 the duct 53 may be connected to either duct 55 or duct 56. A suitable form is illustrated wherein the ducts 53, 55 and 56 have ports concentric about a center and open upon a face of a plate. A movable member is pivotally mounted at the center of the three ports and bears against the face containing the duct ports. A depression on the side of the movable member is always open to the port of the duct 53 and is capable of opening communication therefrom to either the duct 55 or the duct 56 by simply turning the movable member about its pivot. A suitable handle is provided to turn the movable member of the valve and a stop is provided to confine the movement to the necessary limits.

40 I will now describe the operation.

45 The music sheet is attached to the take-up roll by its ring in the usual manner. The rod 16 is then moved to its playing position, the take-up roll having been moved by hand until the music sheet lifts the arm 44 out of its depression 40, in the take-up roll 12.

50 The starting lever (not shown) which operates the rod 24 to close the switch 25, is now operated to close the switch to start the motor 27. This starts the suction pump 28 which is the main source of power to supply the exhaust to the several parts of the 55 instrument.

At the completion of the playing of the selection, the perforation 32 opens, operating the primary valve in the valve box 31, causing the pneumatic 20 to be exhausted with a consequent operation of the extension 21 and the lug 22. This causes the winding and rewinding mechanism to be reversed and the sheet to be rewound.

60 As soon as the diagonal edge 60, of the end of the sheet, uncovers the groove or notch 40, the end of the arm 44, under the action of the spring 49, drops thereinto. This turns the shaft 43 causing the crank 45 to lift the valve 46 which will, when raised, uncover the valve seat 52 of the duct 53. If the valve 54 is set to connect the ducts 53 and 56 together, the stop pneumatic will be operated in a manner already described. This causes the switch 25 to be operated with a consequent stopping of the source of air tension 28. If the valve 53 is set so that the ducts 53 and 55 are connected, then the replay pneumatic 17, upon the opening of the duct 32, will immediately be collapsed. This collapsing of the pneumatic 17 will cause a movement of the rod 16 to the right and cause the winding and rewinding mechanism to be set for winding the music again upon the take-up roll. As long as the valve 54 is set for replay, it is obvious from the above that the selection will continuously be played, rerolled and replayed.

65 It is to be noted that the mounting of all of the mechanism and connections upon the tracker box and its base board, permits of the ready removal of the unit without disturbing any of the connections. It will also be noted that the arrangement of the valve and shaft are such that the parts will lie close to the rear of the tracker box and consequently occupy little space. At the same time, they are not exposed to the dust in the front of the tracker box.

70 While I have described in detail an embodiment of my invention, I desire to have it understood that the drawings are not merely illustrative, that I do not limit myself to the exact structure shown and described and that modifications and changes may be made without departing from the spirit of my invention and within the scope of the appended claims.

75 Having described my invention, what I claim and desire to secure by Letters Patent is:—

80 1. In combination a tracker box supporting board, a tracker box, take-up roll and a stop-replay mechanism supported thereon, the said mechanism comprising a stop pneumatic, a replay pneumatic, a valve seat having communication with the stop pneumatic and the replay pneumatic, controlling means for selectively connecting the valve seat with either the stop pneumatic or the replay pneumatic, a valve controlling the passage 85 125 130

of air at the valve seat, the take-up roll having a depression in its body portion and means controlling the operation of the valve and having a portion in position to enter the depression when the same is uncovered by the note record and be raised out of the depression when the note sheet is rolled upon the take-up roll.

2. In combination a tracker box supporting board, a tracker box, take-up roll and a stop-replay mechanism supported thereon, the said mechanism comprising a stop pneumatic, a replay pneumatic, a valve seat having communication with the stop pneumatic and the replay pneumatic, controlling means for selectively connecting the valve seat with either the stop pneumatic or the replay pneumatic, a valve controlling the passage of air at the valve seat, the take-up roll having a depression in its body portion, a shaft having a crank at its end, the crank being in position to engage and lift the valve, an arm connected to the shaft and in position to enter the depression when the same is uncovered by the note record and be raised out of the depression when the note sheet is rolled upon the take-up roll.

3. In combination a tracker box supporting board, a tracker box, take-up roll and a stop-replay mechanism supported thereon, the said mechanism comprising a stop pneumatic, a replay pneumatic, a valve seat having communication with the stop pneumatic and the replay pneumatic, controlling means for selectively connecting the valve seat with either the stop pneumatic or the replay

pneumatic, a valve controlling the passage of air at the valve seat, the take-up roll having a depression in its body portion, a shaft having a crank at its end, and having its axis substantially in line with the valve, the crank being in position to engage and lift the valve, an arm connected to the shaft and in position to enter the depression when the same is uncovered by the note record and be raised out of the depression when the note sheet is rolled upon the take-up roll.

4. In combination a tracker box supporting board, a tracker-box, take-up roll and a stop-replay mechanism supported thereon, the said mechanism comprising a stop pneumatic, a replay pneumatic, a valve seat having communication with the stop pneumatic and the replay pneumatic, controlling means for selectively connecting the valve seat with either the stop pneumatic or the replay pneumatic, a valve controlling the passage of air at the valve seat, the take-up roll having a depression in its body portion, a shaft having a crank at its end, the crank being in position to engage and lift the valve, an arm connected to the shaft and in position to enter the depression when the same is uncovered by the note record and be raised out of the depression when the note sheet is rolled upon the take-up roll, the valve and shaft being at the rear of the tracker box, the arm extending through an opening in the back board of the tracker box.

In testimony whereof I affix my signature.

TOLBERT F. CHEEK.
